UNITED STATES PATENT OFFICE.

WILLIAM H. HOWE, OF CHICAGO, ILLINOIS.

COMPRESSOR.

1,225,817.

Specification of Letters Patent. Patented May 15, 1917.

Application filed December 1, 1914. Serial No. 875,083.

To all whom it may concern:

Be it known that I, WILLIAM H. HOWE, a citizen of the United States, and a resident of Chicago, county of Cook, and State of Illinois, have invented certain new and useful Improvements in Compressors, of which the following is a specification.

My invention relates generally to compressors and has more particular reference 10 to machines for compressing refrigerating agents.

The general object of my invention is to provide a compressor wherewith it shall be possible to compress the refrigerating agent 15 more rapidly, more efficiently, and more economically than has been possible with compressors hitherto devised.

A further object of my invention is to provide a refrigerant compressor which 20 shall be simple to construct, easy to maintain and in which the parts shall be so constructed and arranged that the incoming relatively cold gases will be maintained in such volume and correlation to the compressor 25 so that it will act to neutralize or reduce the heat generated by the compression of the gases to the end, that all of the parts may be maintained at such temperature as will insure the best results.

30 A further object of my invention is to provide a refrigerant compressor in which it shall be possible to receive, compress, and discharge a full charge of the refrigerant at each operation, in which there can be no 35 possible injury caused by a relatively non-compressible substance finding its way into the space between the piston and the head, and which in normal operation shall be practically gas tight at the head.

40 My invention consists generally in the arrangement, construction, and co-operation of the parts whereby the above named objects, together with others which will appear herein after, are attained.

45 My invention will be more readily understood by reference to the accompanying drawings which illustrate preferred embodiments thereof, and in which—

Figure 1 is a vertical section through a 50 tandem cylinder compressor embodying my invention;

Fig. 2 is a vertical sectional view on the line 2—2 of Fig. 1;

Fig. 3 is a top plan view of the machine, parts being removed better to disclose the 55 cylinder construction;

Fig. 4 is a transverse sectional view on the line 4—4 of Fig. 1;

Fig. 5 is a vertical detailed sectional view on the line 5—5 of Fig. 1 and showing the 60 arrangement of the gas inlet and discharge chambers;

Fig. 6 is a side elevation of the piston removed to illustrate the means of supplying oil to the wrist pin; and 65

Figs. 7 and 8 are detailed views illustrating the operation of the safety head.

Many objections have been urged against the refrigerant compressors hitherto devised. In some much gas passes from the 70 compression side of the machine into the crank case, there expands and causes refrigeration, thereby cutting down the effective operation of the machine. Furthermore, a high pressure is thus created in the 75 crank case and as a result an excessively long gland must be provided to prevent leakage. This of course greatly increases the friction and uses up much of the power required to operate the machine. Realizing that the highest efficiency can only be obtained by discharging a full cylinder of 80 gas at each stroke various constructions have been devised to enable the piston to operate practically metal to metal with the 85 head without danger of breaking other parts of the machine. The most usual construction for this purpose is the so-called safety head, which is a spring pressed plate seated at the upper end of the cylinder. The 90 heads as hitherto devised, however, are objectionable because the seat soon becomes scratched and gas constantly escapes through the recesses thus formed with the result that the compression is lost. 95

I have devised a machine in which a full charge of gas can be taken into the cylinder and fully compressed and discharged; in which injury to the mechanism is impossible even though relatively non-compressible 100 matter becomes interposed between the piston and the head, or in case the discharge valve fails to open, and in which there is practically no leakage of gas when the parts are in normal condition. I have furthermore developed a machine in which the gas 105

escaping from the high pressure side of piston to crank case is practically negligible.

Having thus described the general objects, purposes and construction of the herein disclosed mechanism embodying my invention I shall now describe same in more detail to the end that a fuller and more complete understanding thereof may be had.

Referring to the drawings, 1 represents the compressor base, 2 the crank case, 3 the cylinders generally and 4 the outer casing.

The crank case is provided with openings, 5 and 6 at which place I secure the bearings 7 and 8 for the operating shaft 9. I shall term these for convenience the outer bearings. The bearing 7 it should be noted, has a closed end 7' so that there is no necessity of packing but the shaft projects completely through the other bearing and I therefore provide a gland 10 therefor.

As will be brought out more fully herein-after, it is not necessary with my construction to provide a gland as long as is customary in similar size machines hitherto devised or to pack the joint so tightly as has been hitherto customary and necessary. In order to relieve the shaft of the excessive thrust caused by the compressive period of the stroke and to permit of a much lighter shaft than would otherwise be necessary I prefer to provide a center bearing, 11.

The cylinder portion of the machine comprises two cylinders 3^a and 3^b and these I cast together in spaced relation thus forming a long chamber 3^c of substantially cylinder length. The upper part of the chamber is divided by a wall 3^d thereby forming a smaller chamber 3^e. The large chamber 3^c is the inlet chamber, being supplied with the expanded gas by the return pipe 15. It should be noted that this chamber extends the full length of the cylinders and for a considerable distance around the circumference thereof. Thus I utilize this relatively cold gas to keep down the heat generated in the cylinders by the compression of the gas. Another valuable feature of this large inlet chamber is that a sufficient supply of gas is always at hand ready to enter the compression chamber and completely fill same. I thereby avoid the undesirable rush of gas through the return or suction pipe at each compressive stroke of the piston. Furthermore I am enabled to provide a number of port openings 16, freely to admit the gas to the cylinder.

The gas enters through the ports 16, passes through the suction valve 17 in the piston 18, is compressed in the chamber 19 and is discharged through the valve 20, and into the outlet chamber 8^e from whence it is carried away by the pipe 21.

Great trouble has been hitherto encountered in preventing the gas, after entering the cylinder, from escaping in the direction

from which the piston is driven, in this case the crank case. In some machines the gas is freely admitted to the crank case but this is undesirable because it is necessary to provide extremely long glands on the drive shaft to prevent escaping of the gas. The friction caused by such long and high pressure glands often represents much of the resistance of the entire machine.

I have devised simple but effective means of preventing such escape of gas which greatly reduce the power loss. For this purpose I built a special form of piston. It is a double piston having two head portions 18^a and 18^b which I shall term respectively upper and lower heads. The heads are connected by central portions 18^c which are cut away as indicated at 18^d to permit gas freely to the piston chamber 18^e. Each head portion is provided with a plurality of piston rings 18^f by means of which the gas is effectually prevented from passing into the crank case in the one instance and from the compression side of the piston in the other. I also seal the space at the ends of the wrist pin 25 in the piston with babbitt or other suitable material as indicated at 30. In this manner I practically isolate the crank case from the system and thereby prevent loss in efficiency due to refrigeration in the crank case.

While describing this part of the machine it will be well to note the novel manner in which I oil the wrist pin 25. In the outer face of the piston I cut grooves 31 and 32 and at the bottom thereof I provide holes 31' and 32' leading to the wrist pin. Thus as the piston moves back and forth over the cylinder wall oil is scraped therefrom, flows down the grooves 31 and 32 and from there through the holes 31' and 32' to the wrist pin. I arrange the grooves 31 and 32 at an angle to the vertical not only better to gather the oil but also to prevent any direct passage along which gas could flow to the lower part of the machine. In this manner I am enabled effectually to lubricate the wrist pin and at the same time seal it against the admission of gas thereto.

It will of course be understood that I maintain a supply of oil 60 in the crank case which is thrown upon the cylinder wall by the movement of the shaft and piston rod.

I make the piston or suction valve 17 of a size substantially the diameter of the piston so that it freely admits the gas therethrough with small movement. It is of course important that this valve be properly seated and that it be guided to its seat in such manner that no portion thereof will become unduly worn. I accomplish this described result by providing the valve with a long stem 17^a and a socket 17^b just over the wrist pin to receive and hold the extreme end portion 17^c thereof. Thus the stem is guided at two points one adjacent the valve 18^a

seat at 17^b and the other at a remote point. By such construction there is no possibility of the valve becoming loose or of seating in any but the desired position.

5 In order that a compressor may work at highest efficiency there should be as nearly as possible a complete discharge of gas during compression. I have already described my novel inlet construction whereby it is 10 possible to get a full charge of gas into the compression chamber for each compressive stroke. I shall now describe how I am enabled to secure a full discharge and still maintain the desired compression. I am 15 aware that safety heads have been provided hitherto for this purpose, but in the practical operation they have proven inefficient because they soon become worn and constantly admit gas to the discharge chamber. 20 In other words, the devices hitherto devised for this purpose are such that so soon as the seat of the safety head becomes scratched, as it will in practice because of the interposition of foreign matter, the result is that 25 there is a constant flow of gas along the grooves or recesses thus formed between the safety head and its seat. So also, if the safety head is slightly raised from its seat because of the interposition of some foreign 30 substance the gas will flow through the space thus formed. Therefore when the piston returns to intake position the high pressure gas on the discharge side of the discharge valve immediately rushes through 35 the aforesaid space along the seat of the safety head and into the relatively low pressure space of the compression chamber. It is obvious therefore, that a full charge 40 of gas can not be taken in to the compression chamber since it is already partially filled by the gas which has returned from the high pressure side. The result of this is that work is done sufficient to discharge all of the gas in the compression 45 chamber to secure an actual compression of or a portion thereof because of the return flow. Therefore, such safety heads do not as hitherto devised accomplish the purpose for which they are intended, viz., to provide 50 a construction in which the compression chamber can be completely filled with gas from the return side effectually compressed and completely discharged at each compressive stroke.

55 I have devised a construction which gives the factor of safety necessary to permit the piston to work practically metal to metal with the head in order to secure a full discharge and which at the same time in normal 60 operation prevents passage of gas at any place except through the regular discharge valve. It comprises a cylindrical piston-like member 41 having a closed bottom 41' and an open top. Seated in the bottom 65 is the discharge valve 20 which is nor-

mally held seated by a spring 43. The safety head is firmly held closed by the large spring 44 acting upon the member 45. The member 45, it will be noted, contains a cylindrical recess 46 for the stem 47 of the discharge valve. Thus normally the gas upon reaching the proper stage of compression opens the valve, 20, passes through the port 49 into the outlet chamber 3^e. In Figs. 7 and 8 I have depicted the working of the safety head. In Fig. 7 I have indicated the position the head 41 often assumes in case a relatively non-compressible material becomes interposed between the piston and the safety head. The head is raised against the pressure of the spring 44. The gas, however, must pass through the regular discharge valve 20 and cannot escape along the cylinder wall because I provide the head 41 with a plurality of packing rings 50 to prevent such escape. In case a relatively large obstruction should become interposed between the piston or for some reason, as by the discharge valve sticking as indicated in Fig. 8, the head simply moves farther away from the seat 52 it uncovers an auxiliary or safety discharge port 53 spaced from the seat and communicating with the discharge chamber 3^e. Thus when the safety head is moved to this considerable extent the compressed gas is permitted to escape through this auxiliary or safety port. It should be obvious therefore, that I have provided the necessary factor of safety which will permit the piston to work practically metal to metal with the discharge head. Furthermore, it should be noted that if the safety head seat 52 should become scratched or if the head should become slightly spaced from its seat that no gas could escape directly into the auxiliary discharge port because it is spaced from the seat and because a spring packing ring is interposed in the safety head therebetween. Again, the gas cannot escape when the head is raised to a small extent, as it is quite frequently in practice, because the safety discharge duct is effectually isolated therefrom. And what is probably more important, no gas can return from the high pressure side into the compression chamber even though the safety head is slightly spaced from its seat or if the seat should become scratched and thereby form grooves. Therefore, I am enabled to take in, compress, and completely discharge a full chamber of gas at each compressive stroke.

In order to cool the machine I admit a cooling medium to the space 4' between the casing 4 and the cylinders. The cooling medium is supplied by the pipe 60, is given a whirling helical motion by the helical or spiral guides 61 and finally passes off through the drain pipe 62. This cooling medium effectually cools the portion of the 120

cylinder not subject to the cold gases of the inlet chamber (see Fig. 4).

From this detailed description of my invention I believe that the objects and advantages are apparent, but since this disclosure will readily suggest to others modified structures wherewith the substantial objects of my invention may be attained, I do not wish to be limited to the specific structure herein shown and described except as may be necessary by express limitations in the claims hereunto appended.

I claim

1. In a refrigerant compressor, parallel cylinders cast in spaced relation and forming a gas chamber therebetween of substantially cylinder length, a partition wall between the upper end of the cylinders and forming a relatively small chamber isolated from the large gas chamber.
2. In a refrigerant compressor, parallel cylinders cast in spaced relation and forming a gas chamber therebetween of substantially cylinder length, a partition wall between the upper end of the cylinders and forming a relatively small chamber isolated from the large gas chamber and gas ports in the small chamber adjacent the upper and lower portions thereof.
3. In a refrigerant compressor parallel cylinders cast in spaced relation and forming a gas chamber therebetween of substantially cylinder length, a partition wall between the upper end of the cylinder and forming a relatively small chamber isolated from the large gas chamber, gas discharge ports in the small chamber adjacent the upper and lower portions thereof and gas inlet ducts formed circumferentially of the cylinder and communicating with the large chamber.
4. In a refrigerant compressor, parallel cylinders cast in spaced relation and forming a gas chamber therebetween and a wall extending between the cylinders and forming a gas chamber isolated from the first mentioned gas chamber.
5. In a refrigerant compressor, parallel cylinders cast in spaced relation and forming a gas chamber therebetween, a partition wall extending between the cylinders and forming a gas chamber isolated from the first mentioned gas chamber, and gas ports in both gas chambers.
6. In a refrigerant compressor, parallel cylinders cast in spaced relation and forming a gas chamber therebetween, a partition wall between the upper ends of the cylinders and forming a gas outlet chamber isolated from the first mentioned gas chamber, and gas ports in the outlet chamber adjacent the upper and lower portions thereof.
7. In a refrigerant compressor, a cylinder, a piston therein for compressing the refrigerant,

erant, a safety head comprising a piston like member, spring means for holding it against the compressive action of the piston, a discharge valve only mounted in the safety head, a discharge chamber adjacent the safety head, a main discharge port spaced above the safety head and communicating with the discharge chamber, and an auxiliary safety port spaced from the safety head seat communicating with said discharge chamber and normally covered by a piston like safety head.

8. In a refrigerant compressor, parallel cylinders cast in spaced relation and forming a gas chamber therebetween extending substantially to the top of the cylinders, a partition wall between the upper end of the cylinders and forming a relatively small gas chamber isolated from the first mentioned gas chamber, piston like safety heads in respective cylinders, main gas discharge ports adjacent the upper end of the discharge chamber, and auxiliary gas ports adjacent the lower end of the gas discharge chamber and normally closed by the safety heads.

9. In a refrigerant compressor, a cylinder, a piston therein for compressing the refrigerant, a piston-like safety head, spring means for holding it against the normal compressive action of the piston, a discharge valve only mounted in the safety head, a discharge chamber adjacent the safety head, a main discharge port spaced above the safety head and communicating with the discharge chamber, an auxiliary safety port spaced from the safety head seat communicating with said discharge chamber and normally covered by the piston-like safety head, and a spring packing ring in the piston-like safety head.

10. In a refrigerant compressor, a cylinder, a piston therein for compressing the refrigerant, a piston-like safety head, spring means for holding it against the normal compressive action of the piston, a discharge valve only mounted in the safety head, a discharge chamber adjacent the safety head, a main discharge port spaced above the safety head and communicating with the discharge chamber, an auxiliary safety port spaced from the safety head seat communicating with said discharge chamber and normally covered by the piston-like safety head, and a plurality of spring packing rings in the outer circumference of the safety head.

11. In a refrigerant compressor, a cylinder, a piston therein for compressing the refrigerant, a piston-like safety head, spring means for holding it against the normal compressive action of the piston, a discharge valve only mounted in the safety head, a discharge chamber adjacent the safety head, a main discharge port spaced above the safety head and communicating with the

discharge chamber, an auxiliary safety port spaced from the safety head seat communicating with said discharge chamber and normally covered by the piston-like safety head, and a spring packing ring in the piston-like safety head between the safety head seat and said auxiliary discharge port.

In testimony whereof, I have hereunto set my hand, this 25th day of November, 1914, in the presence of two subscribing witnesses. 10
